T. H. LLOYD

UMBRELLA RUNNER

Filed Jan. 14, 1922

UNITED STATES PATENT OFFICE.

THOMAS HUXLEY LLOYD, OF INVERNESS, FLORIDA.

UMBRELLA RUNNER.

Application filed January 14, 1922. Serial No. 529,300.

To all whom it may concern:

Be it known that I, THOMAS HUXLEY LLOYD, a citizen of the United States, and resident of Inverness, in the county of Citrus and State of Florida, have invented certain new and useful Improvements in Umbrella Runners, of which the following is a specification.

This invention relates to umbrellas, having references particularly to an improved umbrella runner.

The invention has for its principal object the provision of a device of this character which is of such construction as to be readily operable without necessity of directly handling the spring-catch and entailing liability of abrading the fingers of a user.

In carrying out my invention I provide a concealed spring-catch having two cam-faces and an intermediate notch, a tubular runner having a longitudinal slot, and a latch extended across said slot for engaging the notch of the spring-catch, and a spring-controlled reciprocative slide for actuating the spring-catch, and means for preventing rotation of the elements, all as hereinafter fully described and specifically set forth in the appended claims.

In the accompanying drawings forming part of this specification, Figure 1 is a side elevation of an umbrella stick having my improved device attached and showing a rib and stretcher in dotted lines;

Fig. 2 is a longitudinal sectional view taken on the line 2—2 of Fig. 1;

Fig. 3 is a cross section taken on the line 3—3 of Fig. 2; and

Fig. 4 is a perspective view of the tubular runner.

In the drawings, 1 indicates a tubular runner having the ordinary peripherally notched and annularly grooved head 3, to which the inner ends of the stretchers are adapted to be swingingly attached, in the usual manner common to all umbrellas.

The runner 1 is provided with a longitudinal slot 4, having tongues 5 extended from each side and a segment 6 which closes the slot 5 at a point midway between its two ends, said segment constituting a latch for engaging a spring-catch hereinafter described. The runner 1 is further provided with radially extended tongues 7, arranged diametrically opposite each other for slidably engagement with grooved bearing members 8, of the reciprocal slide which com-

prises a cylindrical casing 9 and sleeves or bearing members 10, which are in frictional contact with the runner 1. These bearing members 10 are respectively provided with an inwardly extended tongue 11, which bears between the longitudinal tongues 5 of the runner 1, whereby rotation of the slide on the runner is prevented.

Mounted within the cylinder 9 and bearing between the tongues 7 of the runner 1 is a contractile spring 12 for automatically actuating the slide in either direction, in a manner as hereinafter described.

The runner 1 is mounted on the usual stick 13, which may be composed of solid wood or tubular metal as may be desired. Mounted within a recess 14 of the stick 13, by means of a suitable rivet, as 15, is the spring-catch comprising a plate-spring 16 and the catch member 17 having a notch 18, for engaging the latch 6, and cam-faces 19 and 20 adapted for contact with the tongues 11 of the slide when the same is reciprocated.

In the operation and use of the invention, when it is desired to raise the umbrella, it is simply necessary to move the slide in the direction of the arrow *a*, Fig. 1 of the drawings, for a sufficient distance to allow the lower tongue 11 to contact with and ride on the cam-face 19 sufficiently to swing the catch 17 out of engagement with the latch 6, whereupon the runner 1 may be moved upwardly on the stick 13 sufficiently to open the umbrella and allow the latch 6 to engage the upper spring-catch 17^a, in the customary manner. To close the umbrella the operation is reversed, that is, the slide is simply pulled in an opposite direction until the upper tongue 11 releases the latch 6 from the notch 18 of the spring-catch, the spring 12 automatically acting to reengage the latch 6 with the notch of the lower spring-catch when the slide is released.

While I have illustrated and described a fair example of my invention, I do not wish to be understood as confining myself to the specific details of mere construction of the elements of my improvements shown, as under the spirit of my invention I believe that I am entitled to employ such variations as may fall within the scope of the appended claims.

Having thus described my invention, what I claim as new and desire to secure by Letters Patent, is:

1. In a device of the character described,

a transversely slotted spring-catch, a slotted runner for accommodating the spring catch, a latch bridging the slot of the runner to receive the slot of the spring catch, and a 5 spring-actuated reciprocal slide for releasing said catch from the latch.

2. In a device of the character described, including an umbrella stick, a spring-catch mounted on said stick, said catch having two 10 cam-faces and an intermediate notch, and a tubular runner having a longitudinal slot and a latch extended across said slot and adapted for engaging the notch of said spring-catch, and a spring-controlled reciprocal 15 slide for actuating the spring-catch, and means for preventing rotation of the slide on the runner.

3. An umbrella operating means comprising a runner provided with a longitudinal 20 slot, a segment bridging the slot midway its ends, a spring catch provided with a transverse slot adapted to operatively receive the segment, and a spring controlled casing

mounted for slidable movement on the runner and having means for moving said catch 25 off of the segment whereby said runner may be operated.

4. An umbrella operating means of the character described comprising a runner mounted for slidable movement upon the 30 stick of the umbrella, spring catches secured within the stick and provided with cammed ends, a segment latch formed on the runner to receive the catches, a cylindrical casing surrounding the runner for non-rotatable 35 slidable movement, bearings formed on the ends of the casing for releasing said catches for engagement with the cammed ends thereof, and a coil spring arranged in said casing to retain and return it to normal position 40 as and for the purpose specified.

Signed at Inverness in the county of Citrus and State of Florida this 9th day of November A. D. 1921.

THOMAS HUXLEY LLOYD.
